UNITED STATES PATENT OFFICE.

CHARLES ELLSWORTH ADAMSON, OF MUNCIE, INDIANA.

DISK-COVER FOR JOB-PRINTING PRESSES.

SPECIFICATION forming part of Letters Patent No. 531,293, dated December 25, 1894.

Application filed January 8, 1894. Serial No. 496,178. (No model.)

To all whom it may concern:

Be it known that I, CHARLES ELLSWORTH ADAMSON, a citizen of the United States, residing at Muncie, in the county of Delaware and State of Indiana, have invented a new and useful Disk-Cover for Job-Printing Presses, of which the following is a specification.

My invention relates to a cover for the ink disk of job presses that are constructed with a thin flat circular disk on which the printing ink is distributed by the press rollers, especially such presses as are commonly known as the "Gordon," and the objects of my invention are, first, to provide a thin cloth cover for the ink disk, to be used in working thin running ink, such as copying ink and others that do not work well on an iron disk; second, to construct a flexible cover having its under side of rubber or impervious material and the upper side of cloth for retaining the ink, and third, to construct a flexible cover with a rubber edge made so as to clamp and hold itself to the ink disk. I attain these objects by the mechanism illustrated by the accompanying drawings, in which—

Figure 1 is a perspective view of the upper part of a Gordon job press, showing the circular ink disk covered with one of my covers. Fig. 2, is a cross section of the disk and cover taken on lines X X of Fig. 1. Fig. 3, is an enlarged view of one end of Fig. 2. Fig. 4, is a section of one edge of a cover showing the rubber edge and the cover made in two parts and glued together. Fig. 5, is a view of the under side of a part of a disk with a cover secured thereon showing a modified form of the fastening edge, and Fig. 6, is a view showing the top of a complete cover with one edge turned up, exposing the self clamping edge which is formed on its under side.

Similar letters refer to similar parts throughout the several views.

The cover consists of three essential parts, but they are combined, all in one piece. The upper part A is of a soft cloth or felt covering the entire upper surface of the cover. Below this cloth is a thin sheet or layer of impervious material B which is made fast to the cloth in the process of manufacture, so that the cover becomes one solid piece. The outer edge of the rubber part of the cover is curved downward having a cord or enlarged edging

C formed on the inner edge, all as shown in Figs. 2, 3, and 6. This edge C serves to clamp under the edge of the iron disk D and to hold the cover firmly in position. When it is desired to remove the cover from the disk one edge is turned up by springing it outward, which will readily release it from the disk, and a similar operation attaches the cover to a disk. I do not confine myself to the rubber corded edge as a means of securing the cover to the disk, as other constructions may be used, one of which I have used quite successfully is shown by a half disk in Fig. 5. In this construction, when the disk cover is cut out of rubber cloth, strips E are left around the periphery of the cover every few inches, and the ends of which are turned over and stitched, forming a loop through which the cord or tape F is passed drawing the ends all toward the center of the cover, thereby holding it firm on the disk, the same as the rubber edging.

In Fig. 4, the rubber edging is shown as being made separate from the main cover. This may prove quite economical in the manufacture of the cover, as the part A, B, may be cut out of rubber cloth and the edging glued or cemented to it at the seam G, all as shown in the said figure.

My covers may be used for water as well as inks and they may be placed on a disk without washing it, which saves time of washing the iron disk in changing the press from one color to another, also saving the ink which would have to be washed off. The ink on the iron disk serves to adhere the cover closely and firmly to it.

It is intended to make the covers of any desired texture and of all sizes to suit the various sized job presses having round or square disks.

Having thus described my invention, I claim the following and desire to secure the same by Letters Patent:

1. The combination with the ink distributing disk of a printing press, of a detachable cover having an ink retaining outer surface and means for securing the cover to the disk, substantially as described.

2. The combination with the ink distributing disk of a printing press, of a detachable flexible cover having an ink retaining outer

surface and a band on its periphery for securing the cover to the disk, substantially as described.

3. The combination with the ink distributing disk of a printing press, of a detachable flexible cover having an ink retaining outer surface, an impervious lining and means for securing the cover to the disk, substantially as described.

4. The combination with the ink distributing disk of a printing press, of a detachable impervious cover having an ink retaining surface and means for securing the cover to the disk, substantially as described.

CHARLES ELLSWORTH ADAMSON.
